UNITED STATES PATENT OFFICE.

FRANK JOHN HETZNER, OF ROCHESTER, INDIANA.

CAR-COUPING.

SPECIFICATION forming part of Letters Patent No. 296,005, dated April 1, 1884.

Application filed January 15, 1884. (No model.)

To all whom it may concern:

Be it known that I, FRANK J. HETZNER, a citizen of the United States, residing at Rochester, in the county of Fulton and State of Indiana, have invented a new and useful Car-Coupling, of which the following is a specification, reference being had to the accompanying drawings.

My invention relates to car-couplings; and it has for its object to provide a device of this character which shall be cheap and simple in its construction and certain in its operation.

The invention consists in the improved construction and combinations of parts hereinabove fully described, and pointed out in the claims.

In the drawings, Figure 1 is a perspective view of a car having my improved coupling applied thereto. Fig. 2 is a longitudinal section of the same. Fig. 3 is a bottom view, and Fig. 4 is a modification.

A represents the car, to the under side of which is secured a bumper, B, of the ordinary construction.

C represents the draw-head, which is secured within the bumper B. The rear end of said draw-head is recessed or cut away, and upon said recessed portion is mounted a coil-spring, a, the rear end of which bears against a cross-beam, b, of the bumper B, and the forward end against the ledge formed upon the draw-head by recessing or cutting away the same. A transverse pin, c, is employed to prevent the forward movement of the draw.

The draw-head C is provided with the usual link or hook opening, d, which extends rearwardly nearly the entire length of the draw-head. Within the draw-head, and at the rear end of the same, is secured the rear end of a spring coupling-latch, D. The forward end is situated at the front end of the draw-head, and is provided with a hooked portion to receive and retain the coupling-hook. Upon the upper side of the draw-head, and at about the center of the same, is located a longitudinal slot, e, which communicates with the draw-head. This slot or opening is adapted to receive a rod extending downwardly from the top of the car, said rod depressing the spring coupling-latch to uncouple the cars by means to be more fully described.

F represents the rod for uncoupling the cars,

the same being mounted in a bracket, f, secured to the outer side of the car and passing through a perforation in the bumper and entering the slot in the draw-head. Upon the bracket f, and at the outer end of the same, is mounted a standard, f', having arms f² at its top, between which is pivoted the end of a lever, G. The upper end of the rod E is provided with arms e', to receive a portion of the lever G, which rests therein, and which depresses the rod E when operated.

H represents a standard or rack-bar secured upon the top of the car, the said bar being provided on its rear side with teeth h, for a purpose to be described.

I represents a bell-crank lever, which is pivoted near the rear end of the lever G, and is provided with a perforation, h, to receive the bent end h' of a rod, h², carrying at its end a block, h³, which engages with the teeth upon the standard H. Upon this rod h² is mounted a coil-spring, h⁴, which bears against the end of the block h³ at one end and against a block, h⁵, at the other end, said block h⁵ being secured to the side of the lever G, and having a perforation for the passage of the rod h².

In applying my coupler to platform-cars, I employ a screw-threaded rod secured in a screw-threaded bracket to the front of the car, whereby the coupling-latch is depressed to uncouple the cars by turning the end of the rod down upon the coupling-latch. The rod, as it will be obvious, need not be screw-threaded its entire length, but only a sufficient distance to allow of the ready working of the same.

The operation is as follows: The link of the adjacent car strikes against the coupling-latch, and depresses the same, which, after the hooked portion of the coupling-hook has entered the draw-head, resumes its normal position and securely retains the hook within the draw-head. When it is desired to uncouple the cars, the bell-crank lever is operated to disengage the block from the teeth of the standard, and the lever G is then depressed, which action depresses the rod E, the end of said rod depressing the coupling-latch, thus allowing the coupling-hook to be removed.

From the foregoing description it will be apparent that by the use of my improvements the operation of coupling is rendered certain, and that the devices for uncoupling the cars

are also certain and effective in their operation.

Having fully described my invention, what I claim as new, and desire to secure by Letters 5 Patent, is—

1. In a car-coupling, the combination, with a draw-head, of a coupling-latch provided at its front end with a hooked portion, and a spring-pressed rod extending upwardly from 10 the under side of the car and passing through the rear end of said latch, substantially as set forth.

2. The combination, with the draw-head having a coupling-latch secured therein, of a 15 rod mounted in a bracket secured to the outer side of the car, a standard secured to said bracket having arms, between which is pivot-

ed one end of a lever, said lever being also connected to the coupling-rod, a standard, H, having teeth h, a bell-crank lever, I, pivoted near the rear end of the lever G, a rod, h², connected with said bell-crank lever, and a block, h³, secured to the end of the rod h², said rod being provided with a coil-spring, which bears against the block h³ at one end and against the block h⁴ at the other end, substantially as set forth.

In testimony that I claim the foregoing as my own I have hereto affixed my signature in presence of two witnesses.

FRANK JOHN HETZNER.

Witnesses:

CHRISTOPHER C. WOLF,

PAUL HETZNER.
